CARD SORTING DEVICE

Arthur W. Feiertag, Athens, Ohio, assignor, by
mesne assignments, to Royal McBee Corporation,
a corporation of New York

Original application June 14, 1948, Serial No.
32,932, now Patent No. 2,525,405, dated October
10, 1950. Divided and this application July 25,
1949, Serial No. 106,581

1 Claim. (Cl. 211—149)

1

The present invention pertains to devices for sorting cards, and more particularly to the selective sorting of marginally perforated cards.

This application is a division of my copending application Serial No. 32,932, filed June 14, 1948, now Patent No. 2,525,405 issued October 10, 1950, entitled "Card Sorting Device."

Cards of the type referred to are provided along one or more edges with one or more rows of perforations which are grouped and identified by suitable indicia to represent desired classifications. In practice, one or a plurality of these perforations are notched or slotted out to the edge of the card, forming a pattern of notches or slots pertaining to a single classification. Such notched and slotted cards may be selectively sorted by passing one or more sorting rods through selected perforations of a group of cards, which perforations represent the desired classification. By then permitting the cards having notches or slots coinciding with the perforations penetrated by the rod or rods to disengage from the latter, while the remainder of the cards remain suspended therefrom, the cards of one or more selected classifications are sorted from a stack of cards.

It is an object of the present invention to provide a card sorting device of the character described which is readily and easily assembled and disassembled and can be readily and easily folded into a compact condition for shipment or storage.

It is a further object of the invention to provide an apparatus of the character described having means for locking different operative parts thereof in suitable positions for the various operations.

These and other objects of the invention will be apparent from the ensuing description and the appended claim.

The apparatus of the invention will be better understood by reference to the accompanying drawings illustrating a preferred embodiment of the invention.

In the drawings:

Fig. 1 is a perspective view of the apparatus of the invention in operative position.

Fig. 2 is a perspective view, showing how the apparatus may be folded up for ease of storage and shipment.

Fig. 3 is a side elevation showing in full lines the apparatus after stacking the cards and also showing, in broken lines, the position of the apparatus for removing selected cards.

Fig. 4 is a fragmentary, detailed view of a notched card, such as are sorted by the apparatus of this invention.

2

Fig. 5 is a plan view, partly in section, of the apparatus of the invention.

Fig. 6 is a front elevation, partly broken away, of the selector mechanism.

Fig. 7 is a cross-sectional view along the line 7—7 of Fig. 5.

Figs. 8 and 9 are enlarged, fragmentary, detailed views taken along the lines 8—8 and 9—9 of Fig. 7, respectively.

Fig. 10 is an enlarged, detailed fragmentary view along the line 10—10 of Fig. 5.

Referring now to the figures of the drawings, the main structural elements of the apparatus are a base 1, supporting a back or frame 2, which, in turn, supports a card tray 3 and a selector mechanism 4. Base 1 is in the form of a dish-like structure having a main or bottom portion 9, front and rear flanges 10 and 11, respectively, and side flanges 12 having horizontal outwardly turned top portions. Base 1 is also provided with beads 9a for reinforcement, and at the rear with upwardly extending brackets 13 on opposite sides of the base. Each bracket 13 is provided with a slot 14 having an upper, circular section 15 and a lower vertical section 16.

Tray 3 comprises a main portion or deck 20, a forward bead 21, rearwardly extending tabs 22 and rearwardly slanting brackets 23 secured to the opposite sides and rearwardly of the tray. Brackets 23 are joined at their outer ends by stop bar 24.

Back or frame 2 is provided with a main portion or face 29 bent backwardly near the sides to provide flanges 30. On face 29 near each edge thereof is a vertical row of horizontal slots 31.

The top of face 29 is bent forwardly to provide a flange 32, and each side flange 30 is cut away and extends upwardly to provide an ear 33 which is separated from flange 32 by a slot 34. The bottom of face 29 is bent rearwardly to provide a flange or shelf 35. Pivoted to the top of frame 2 is a member 36 bent to form a vertical extension 29a of face 29 and a horizontal shelf 36a having an upwardly and outwardly turned edge portion. Shelf 36a is provided with a vertical partition 37

40 and a spring 38 to receive and retain a supply of selector rods 88. Secured to each end of vertical extension 29a and extending forwardly therefrom is an arm 39 receiving and holding a rubber grommet 40, as shown in Fig. 7 and, in broken lines, in Fig. 5.

As best shown in Fig. 2, the bottom portion of each side flange 30 is cut away to provide a rearwardly curving, recessed ear 42 and above each ear 42 is a vertical, oblong slot 43. Frame 2 is 55 pivoted to base 1 by a keeper bar 44, secured by

55

nuts 45, extending through oblong slots 43 and appropriate passages in brackets 13. Lugs 46 secured to ears 42 extend through and engage the sides of slots 14.

The selector mechanism 4 is pivoted to frame 2 by means of arms or brackets 50 and pivot pins 51, the latter extending through ears 33 of flanges 30. Each bracket 50 is in the form of a sheet metal strip so cut and bent as to provide an inwardly extending flange 52 cut away at the rear to provide a shoulder 53, and is further provided with an inwardly bent tab or arm 54 to receive a pivot pin 55. Selector tray 60 and the elements associated therewith are pivoted to brackets 50 by means of the pivot pins 55.

The apparatus is shown in operative position in Fig. 1, and is shown folded up for storage or shipment in Fig. 2. In folding up the apparatus, it is merely necessary to raise and tilt the tray 3, using stop bar 24 as a fulcrum, sufficiently to disengage tabs 22 from slots 31, then lower the tray until it rests upon and nests within base 1. Then frame 2 is lifted to engage the bottom of slot 43 with keeper bar 44, which results in raising lugs 46 into a position such that, as frame 2, pivoted on keeper bar 44 is swung forward, lugs 46 slide upwardly through the circular section 15 of slot 14. Frame 2 is then merely bent forward into the position shown in Fig. 2. Finally, selector 4 and brackets 50, pivoted on pins 51, are folded backwardly into the position shown. In this position, shoulder 53 of bracket 50 rests adjacent to notch 34, and all the various parts are compactly and securely brought together.

Selector mechanism 4 comprises a tray portion 60 which is pivoted to arms 54 by means of pivot pins 55, as mentioned above, and a head member or selector rod actuating bar 61. Tray 60 is defined by forward and rearward longitudinal bars 62 and 63, respectively, transverse or end bars 64, and transverse bottom bars 65. Forward bar 62 is provided with an upper row of perforations 66 and a lower row of perforations 67 shown in section in Figs. 5 and 7 and in elevation in Fig. 6. Rearward bar 63 is provided with upper and lower slots 68 and 69, respectively, in alignment with upper and lower rows of perforations 66 and 67, respectively. Head member 61 is also provided with upper and lower rows of countersunk perforations 66a and 67a, respectively, corresponding to and in alignment with upper and lower rows of perforations 66 and 67, respectively, of forward bar 62. The countersinking of perforations 66a and 67a is more clearly shown in Fig. 7.

Head member 61 is carried by plungers 75 secured to each end of the head member and which slide through complementary channels 76 in end bars 64 of tray 60. Head member 61 is also provided with a locking plate or slide 77 which is slidably secured to the face of head member 61 by the ends of plungers 75 extending through oblong slots 77a, and by means of washers 75a and retainers 75b. Locking plate 77 is provided with upper and lower rows of perforations 78 and 79, respectively, in alignment with perforations 66a and 67a, respectively, of the head member proper. Locking plate 77 is also provided with an inwardly extending flange or ear 80 at one end thereof, which is received within a recess 80a in head member 61. Within recess 80a and secured between the inner side of flange 80 and the adjacent side of recess 80a, is a spring 81 which normally acts to urge locking plate 77 out-

wardly or to the left, as viewed in Fig. 5, so as to hold perforations 78 and 79 out of alignment with perforations 66a and 67a of head member 61. Selector rods 88, each having a head 89 and an annular groove 90, are inserted through perforations 78 and 79 of locking plate 77 and through corresponding perforations 66a and 67a of head member 61 when the latter is in closed position, as shown by full lines in Fig. 5.

The design of the countersunk perforations 66a and 67a of head member 61 and of locking plate 77 is such that the selector rods can be inserted while locking plate 77 is in normal, unaligned position. This is accomplished by having the perforations 66a and 67a countersunk, as described, and by designing oblong slots 77a so as to limit the disalignment of plate 77 to a position such that it covers about half of each perforation 66a and 67a. In this position, the selector rods 88 can be inserted without moving plate 77 with fingers against spring 81, but once the rods are inserted, slide 77 is deflected to right by countersunk holes, the locking plate 77 will engage the grooves 90 when selector rod 88 limits in slot 68 and 69 and prevent outward movement of the rods until plate 77 is pushed or pulled to the right. This can be easily accomplished by placing a finger at top and bottom of slide 77 (as shown in Fig. 6) and pulling or pushing slide 77 to right against tension of spring 81. The selector rods 88 are thus easily inserted, are securely locked in place when head member 61 is extended to inoperative position, as shown by dotted lines in Fig. 5, as well as during rotation of the selector mechanism, and are easily removed.

Secured to each end of head member 61 by means of bolts 91 is a cap or bumper 92, which engages the underside of flanges or ears 52 when the selector mechanism is pivoted through 180° to its inverted position.

Each plunger rod 75 is provided with an annular groove 95 near its forward end. Each groove 95, when head member 61 and plunger rods 75 are in inward, operative position, is in alignment with a recess or channel 96, within which a ball bearing 97, urged by a spring 98, engages the adjacent groove 95. Thus, when in inward, operative position, the plunger rods and head member are yieldably locked in place. However, when it is desired to pull head member 61 into extended, inoperative position, this may be readily accomplished by exertion of a slight pull on the head member 61. This yieldable locking means is operative to hold the head member in inward, operative position and prevent it from falling into the extended position as the selector mechanism is revolved about its axis.

The outer or rearward end of each plunger rod 75 is provided with a pin 99 extending outwardly in a horizontal position, and at such a point that when the head member 61 and plungers 75 are in inward, operative position, the pins 99 clear the ends of flanges 52, so that the selector mechanism may be rotated about its horizontal axis. However, when the head member and the plunger rods are in extended, inoperative position or at any intermediate position, pins 99 engage flanges 52, and thus prevent rotation of the selector mechanism.

A cushion to prevent shock, noise and jarring as the head member 61 is pulled outwardly into inoperative position, is provided by two springs 100, one of which is shown in Fig. 5 and to an enlarged scale in Fig. 10. Each of these springs 100 is located in a recess or channel 101 in an end

bar 64 and is secured to a pin 112. As the head member 61 and the plunger rods 75 are pulled outwardly into inoperative position, the pins 99 slide through slots 113 in the sides of end bars 64 until the pins engage the springs 110, which serve as limit members.

In operation, the apparatus is assembled and brought into the position shown in Fig. 1. Selector rods 88 are inserted in perforations 78 and 79 of locking plate 71, thence through perforations 66a and 67a of head member 61 and on through perforations 66 and 67 of forward bar 62. Then head member 61 is pulled outwardly into extended, inoperative position. Marginally punched cards 120 provided with upper and lower rows of marginal perforations 121 and 122, respectively, are then stacked in tray 60 with their perforated margins downward. It will be noted that certain of the marginal perforations, such as 121a and 122a, are slit all the way through to the edge of the card. With cards 120 in position, and with head member 61 in extended, inoperative position and selector rods 88 placed in the proper position, the head member 61 is pushed inwardly until it abuts against bumper washer 92a and tray 60, thus pushing the selector rods through the marginal perforations of the cards 120 and engaging their tips in slots 68 and 69 of rear bar 63 of tray 60. The selector mechanism is then pivoted forwardly through an arc of 180° on pivot pins 55 as shown by the broken lines in Fig. 3. The selected cards, i. e., those engaged only by rods 88 engaging slits 121a and 122a, drop out onto the deck of tray 3 and may be removed, after which the selector mechanism may be swung around into its original position for rearrangement of the selector rod 88 or for inserting a new stack of cards 120.

It will be apparent that the apparatus of the invention adds to the mechanisms of this class, a number of advantageous features making for ease of assembly and disassembly, compactness when in collapsed condition and efficiency of operation.

While I have shown the preferred form of my invention, it is to be understood that various changes may be made in its construction by those skilled in the art without departing from the spirit of the invention as defined in the appended claim.

Having thus described my invention, what I claim and desire to secure by Letters Patent is:

A card selector comprising a base, a frame,

means swingably connecting said frame at its bottom portion to the rear portion of said base for releasably locking the frame in an upright position and for movement of the frame from an upright vertical position to a horizontal folded position, said means including a slot formed in the lower portion of the frame and being parallel with the longitudinal direction of the frame, a pivot secured to the base member and extending into said slot in the frame, a pin projecting from the frame, said pin being spaced from and directly below said slot in the frame, said base member having a slot formed therein with a lower vertical pin seating portion and an upper arcuate portion for receiving said pin, said vertical pin seating portion being spaced from and directly below said pivot in the base member and said upper arcuate portion having the pivotal axis of said frame about said pivot as its center of curvature; a horizontally disposed card-receiving tray, means connecting the tray to the frame for vertical movement therealong from a position in immediate juxtaposition with said base to a position spaced from and above said base, the last-named means including a bail member surrounding the frame and having its rear portion disposed at a level above the top surface of the tray approximately the same distance as the width of said frame, means for releasably locking the tray in a position spaced from and above said base, a sub-frame, means swingably mounting the sub-frame at the top of the frame for movement from an operative horizontal position at the front of the frame to an inoperative position parallel with and extending in the direction of the frame at the rear of the frame, and a card selector mechanism rotatably mounted on the sub-frame for movement with said sub-frame.
